UNITED STATES PATENT OFFICE.

JAMES JOSEPH KEON, OF OWEN SOUND, ONTARIO, CANADA, ASSIGNOR TO THE WILLIAM KENNEDY & SONS, LIMITED, OF OWEN SOUND, CANADA.

STOPLOG WINCH.

Application filed September 18, 1925. Serial No. 57,127.

To all whom it may concern:

Be it known that I, JAMES JOSEPH KEON, of the city of Owen Sound, in the county of Grey, Province of Ontario, Canada, a 5 subject of the King of Great Britain, have invented certain new and useful Improvements in Stoplog Winches, of which the following is a specification.

This invention relates to winches such as 10 used in connection with dams for removing logs which are used for controlling the height of water. These dams include a series of spaced concrete piers arranged across the stream, said piers being grooved 15 or recessed to receive a series of logs which extend from pier to pier to complete the dam. By removing or replacing one or more of these logs, the level of the water may be lowered or raised as the case may 20 be, and it is to the winches which are used for removing these logs that my invention relates. As the posts or piers are often placed irregular distances apart it has been necessary in a complete installation to supply 25 winches of various lengths, which increases the cost of making the complete installation very materially.

My object is therefore to devise a winch 30 which may be adjusted to any desired length within the limits of the device, thus enabling a standard winch to be used for all positions, its length being adjusted when the winch is being installed, or if the winch be mounted on a track extending 35 across the dam, the same winch may be used for all the sections, the length of the winch being adjusted as may be necessary to suit the distance between piers.

I attain my object by means of the constructions hereinafter described and illustrated in the accompanying drawings in which—

Fig. 1 is a plan view of my improved winch;

Fig. 2 is a side elevation of the same; and Fig. 3 an end elevation of the same.

In the drawings like numerals of reference indicate corresponding parts in the different figures.

The device comprises a frame formed 50 of two sections A and B slidable longitudinally of one another whereby the length of the frame may be varied as desired.

The section A comprises a pair of longitudinal frame members 1 of channel section

connected together by transverse frame members 2, 3, 4, 5, 6 and 7 and 8', while the section B comprises a pair of longitudinal frame members 8 connected together by transverse frame members 9, 10, 11 and 12. 60 The frame members 8 are spaced apart so that they will receive between them the longitudinal frame members 1, guides 13 being formed in which the ends of the members 8 are slidable and by means of 65 which said frame members 8 are held in alignment with the frame members 1.

The left hand end of the frame, having reference to Figs. 1 and 2 of the drawings, is supported by means of a bogey truck 17 70 of any suitable type, which truck is connected with the transverse members 2 and 3 connecting the inner frame members 1.

The right hand end of the frame is supported by means of a similar bogey truck 75 18, which truck is connected with the transverse frame members 9 and 10 which connect the outer frame members 8. In practice suitable tracks will be provided on which the wheels of the trucks will run. 80

The winch will be provided with a pair of hoisting rams 19 and 20, one adjacent each end of the frame.

For adjusting the frame to vary the distance between the rams and the distance 85 between the trucks, I mount on each of the inner frame members 1 a rack 14 with which meshes a pinion 15 fast on a shaft 16 journalled in suitable bearings on the outer frame members 8. This shaft is provided with a squared end on which a suitable crank may be fitted for rotating the shaft or may be rotated by motor power by means of suitable gearing.

The outer frame members 8 will be of 95 such a length that when the frame is adjusted so that the rams and trucks are at their maximum distance apart the end of the members 8 will rest on the transverse frame members 3 directly over the bogey 100 truck 17 and the inner frame members 1 will be of such a length that when the frame is adjusted so that the rams and trucks are at their maximum distance apart the ends of said members will rest on the transverse frame members 9 and 10 directly over the bogey truck 18. There is therefore no danger of the center of the frame sagging as would be the case if the longitudinal frame members of one section were 105 110

not of sufficient length to reach over the truck of the other section when the rams and trucks are at their maximum distance apart.

- 5 The hoisting rams 19 and 20 carry as usual at their lower ends hooks 21 by means of which the stop logs are engaged and lifted. As the object of my invention is to provide a construction in which the distance apart of these rams may be varied as desired, the ram 19 is vertically movable in a frame 35 carried by the transverse members 11 and 12 and a suitable guide 22 for its upper end is supported by means of braces 15 23 secured to the longitudinal frame members 8.

The ram 20 is vertically movable in a frame 24 carried by the transverse members 4 and 5 and a suitable guide 25 for its upper end is supported by means of braces 26 secured to the longitudinal frame members 1.

Each ram, as is common in the art, is provided with a rack whereby it may be raised or lowered by means of a suitable pinion 27. The pinion 27 for the ram 20 is mounted on a shaft 28' which is connected by a train of gears to shaft 28, which shaft is driven by means of a suitable gearing 29 from a main drive shaft 30. The mechanism for driving this main drive shaft is supported by the longitudinal frame members 1, and therefore there will at no time be a variation of distance between the said driving mechanism and the ram 20. The ram 19 is actuated by means of a pinion 31 driven by means of suitable gearing 32 from a shaft 33 driven by suitable gearing 34 and 29 from the main drive shaft 30. Owing to the variation in position of the ram 19 relative to the driving mechanism, the shaft 33 is therefore preferably formed for a part of its length of square cross section and the pinion 32^a of the gearing 32 is arranged to slide longitudinally thereof. Other arrangements than that shown might, however, be devised to permit of longitudinal movement of the pinion 32^a on the shaft 33 but preventing rotary movement of the pinion relative to the shaft.

A motor may be provided for driving the main drive shaft 30, or manually operated means, or both as is common in the art.

From the above description it will be seen that I have devised a winch which will satisfactorily attain the object of my invention as set out in the preamble of this specification. When it is desired to adjust the length of the winch, it is merely necessary to apply a suitable crank to the shaft 16 and rotate the shaft in the desired direction or suitable gearing may be provided so that shaft 16 can be rotated by means of the hoisting motor on the winch, if a motor is provided.

What I claim is:

1. In a stoplog winch, the combination of a frame; a pair of rams mounted on said frame; and common means for actuating said rams simultaneously, said frame comprising a pair of sections movable longitudinally relative to one another and each section having a ram mounted thereon, said means for actuating the rams being adapted to permit relative movement of the frame sections. 70

2. In a stoplog winch, the combination of a frame, said frame comprising a pair of sections movable longitudinally relative to one another and each section having a ram mounted thereon; and means for moving said sections longitudinally of one another. 80

3. In a stoplog winch, the combination of a frame; a pair of rams mounted on said frame; means for actuating said rams, said frame comprising a pair of sections movable longitudinally relative to one another and each section having a ram mounted thereon; and means for moving said sections longitudinally of one another. 85

4. In a stoplog winch, the combination of a frame, said frame comprising a pair of sections movable longitudinally relative to one another and each section having a ram mounted thereon; and means for moving said sections longitudinally of one another comprising a rack on one of said sections; a shaft journaled in the other sections; and a gear on said shaft meshing with said rack. 90

5. In a stoplog winch, the combination of a frame; a pair of rams mounted on said frame; and means for actuating said rams, said frame comprising a pair of sections movable longitudinally relative to one another and each section having a ram mounted thereon; and means for moving said sections longitudinally of one another comprising a rack on one of said sections; a shaft journaled in the other section; and a gear on said shaft meshing with said rack. 105

6. In a stoplog winch, the combination of a frame comprising two sections movable longitudinally relative to one another; a pair of rams, one on each section of the frame; gearing for actuating each of said rams; means on one of said sections for driving said gearing; and a shaft journaled in the other section driven by said means, the gearing for actuating the ram on said last mentioned section including a pinion slideable longitudinally on but rotatable with said shaft. 115

7. In a stoplog winch, the combination of a frame comprising two sections movable longitudinally relative to one another; a pair of rams, one on each section of the frame; gearing for actuating each of said rams; means on one of said sections for 120

driving said gearing; a shaft journalled in the other section driven by said means, the gearing for actuating the ram on said last mentioned section including a pinion slidale 5 longitudinally on but rotatable with said shaft; and means for moving said sections longitudinally of one another.

8. In a stoplog winch, the combination of a frame comprising two sections movable 10 longitudinally relative to one another; a pair of rams, one on each section of the frame; gearing for actuating each of said rams; means on one of said sections for driving said gearing; a shaft journalled in 15 the other section driven by said means, the gearing for actuating the ram on said last mentioned section including a pinion slidale longitudinally on but rotatable with said shaft; means for moving said sections 20 longitudinally of one another comprising a rack on one of said sections; a shaft journalled in the other section; and a gear on said shaft meshing with said rack.

9. In a stoplog winch, the combination of a frame comprising two sections movable 25 longitudinally relative to one another; a pair of rams, one on each section of the frame; a bogey truck supporting one end of each frame section, the other end of each section when the rams are at their 30 maximum distance apart lying over the truck of the other section.

10. In a stoplog winch, the combination of a frame comprising two sections movable 35 longitudinally relative to one another; a pair of rams, one on each section of the frame; a bogey truck supporting one end of each frame section, the other end of each section when the rams are at their maximum 40 distance apart lying over the truck of the other section; and means for moving said sections longitudinally of one another.

Signed at Owen Sound this 20th day of August, 1925.

JAMES JOSEPH KEON.
